ELECTROLUMINESCENT GENERATOR

Max Solow, Silver Spring, Md., Nathaniel L. Coleburn, Washington, D.C., and Raymond C. Wiley, Rockville, Md., assignors to the United States of America as represented by the Secretary of the Navy

Filed July 26, 1960, Ser. No. 45,509

3 Claims. (Cl. 250—84)

(Granted under Title 35, U.S. Code (1952), sec. 266)

The invention described herein may be manufactured and used by or for the Government of the United States of America for governmental purposes without the payment of any royalties thereon or therefor.

This invention relates generally to the field of solid state physics and is more particularly concerned with a method and a device for generating a short intense pulse of light or a burst of electrons.

This invention utilizes properties of certain metal oxides which contain F' centers. The F' center is a peculiar type of defect in the crystal lattice characterized by the fact that a metal atom is missing from its position in the crystal lattice. In place of the missing atom is found an electron pair. The oxides of the following metals are known to contain these F' centers: aluminum, zinc, magnesium, cadmium, indium and gallium.

This invention also utilizes a phenomenon known as the "electro-acoustic" or the acoustic-electric effect. That is, the phenomenon when a shock wave passes through a material, [generally a metal or a semiconductor although in some cases the effect has been observed in insulators] it sweeps before it a sheet of electrons. The electrons are, in the case of a metal, probably conduction electrons.

It is an object of this invention to provide a method for the generation of a pulse of light which is intense and yet of sufficiently short duration for use in ultra high speed photography.

Another object of this invention is to provide a solid state device which acts as a convenient source of electrons.

Another object is the provision of a novel high intensity light source of short duration which is rugged and durable.

Another object is the provision of a new and improved light and electron generator.

These and many other objects will become more readily apparent to those skilled in the art when the following specification is read and considered along with the attendant drawings wherein like numerals designate like or similar parts throughout the several views and in which:

FIG. 1 is a view, partly schematic, which indicates one preferred embodiment of the invention;

FIG. 2 is a diagrammatic representation of a cross-section of the F' center forming metal oxide of FIG. 1;

FIG. 3 is a diagrammatic representation of the oxide of FIG. 2 showing the material as a shock wave sweeps through it;

FIG. 4 indicates a cross-section of the oxide of FIG. 2 as the shock wave reaches the free surface; and

FIG. 5 indicates the oxide of FIG. 2 as the electrons begin leaving the free surface of the oxide.

Referring now to FIG. 1, a generator 10 is composed of a thick porous layer of metal oxide 11. As stated hereinbefore, the metal oxide may be the oxide of any available F' forming metal such as aluminum oxide, zinc oxide, magnesium oxide, cadmium oxide, indium oxide or gallium oxide. At once surface of the oxide layer is bonded a sheet or block of metal 12. The composition of this layer 12 is not critical, for the sake of convenience, however, it may be desirable to utilize a metal whose oxides are known to form F' centers and to oxidize one

2

surface of this metal to chemically form the oxide layer 11. Thus, if aluminum is utilized as the metal 12 the surface may be treated with an acid such as phosphoric or nitric in order to produce a thick porous coating of

5 oxide.

An explosive material 13, which may be any high explosive, abuts the surface of metal 12 opposite from the oxide layer 11. A typical generator may employ the explosive known as composition B which is a mixture

10 of RDX, TNT with small amounts of wax and polyisobutylene. A plane wave generator shown schematically at 14 is employed to generate a planar detonation wave to initiate the explosive 13 thereby to impinge the metal 12 and the oxide 11 with a planar shock wave.

15 These plane wave generators may conveniently be an air lens, as is well known to those skilled in the art.

A collar 15 is secured to the free surface 28 of oxide 11, while a light transmitting plate 16 is fixed to the opposite end of the collar 15 thereby providing a closed 20 space adjacent to the free surface of the oxide, which space may be evacuated in order to increase the efficiency of operation of the device.

A source of actinic radiation 17 is placed some distance from the oxide layer 11. This source of radiation may 25 conveniently be a radioactive material light source, an electron source, or a source of X-rays. For convenience, a light source may be employed as the source 17. As shown in the figure, the beam 19 from the source 17

30 impinges upon a half-silvered mirror 18 and part of it is directed upwardly as shown at 21 and discarded. The remainder 22 impinges on the surface 28 of the oxide. The light beam impinging on layer 11 serves to activate the layer preparatory to the passage of the explosive wave through the oxide. Each oxide is characterized by a 35 particular activation energy, that is, the energy required to liberate an electron from the F' centers. Thus, for aluminum this energy is 2.64 electron volts. Accordingly, if the layer 11 is aluminum oxide, it may be desirable that the light employed to illuminate its surface and 40 activate or trigger it, be in the neighborhood of 4700 Å. and may be in the range from about 4500 Å. to 5500 Å.

The light generated by the apparatus is emitted from 45 the free surface 28 of the oxide layer 11 as a light beam 23 which is directed by mirror 18 as beam 24 to a device 25 for utilizing the light. This device may conveniently be a camera or a strip of film.

In the event that it is desired to utilize the electrons generated by this device rather than the light, a grid 26 50 may be positioned at or near the free surface of layer 11 in order to control or direct the beam of electrons toward a suitable target [not shown].

The operation of this device may be readily understood by referring to FIGS. 2, 3, 4 and 5. The theory of operation, while it is believed to be accurate, is advanced only 55 as one possible explanation of the observed operation of the device.

As shown in FIG. 2, the oxide layer contains a plurality of F' centers. At the free surface of this oxide layer, a layer 27 of oxygen atoms is adsorbed. The atoms in this layer 27 contain one negative charge, that is, they 60 contain a surplus electron. The triggering radiation, bearing the notation H₂, does one of two things as it impinges upon the surface of oxide 11. Either it impinges upon an adsorbed oxygen atom or it penetrates slightly 65 into the oxide layer. If the radiation impinging upon the adsorbed oxygen atom has sufficient energy it excites the "excess" electron in the adsorbed oxygen and the electron is emitted. The neutralized oxygen atom combines with a neighboring charged atom to form a molecule of oxygen gas and to give off a second electron. The electrons emitted by this process may move either into the space 70 surrounding the free surface 28 of the oxide layer 11

or they may be directed into the oxide layer. Those electrons that are directed into the oxide may impinge upon an F' center. The electrons trapped at the F' centers behave similarly to atomic electrons and may be thought of as moving about the F' center in Bohr orbits. If the impinging electron from the oxygen atoms contains sufficient energy, it may knock out one of these electrons thereby forming an F center which is similar to an F' center but contains only one electron. In a material which customarily contains F' centers, this F center may be thought of as an electron trap since an electron moving through the material would tend to be attracted to the effective positive charge of the F center and be captured to reform an F' center.

Some of the triggering radiation bypasses the adsorbed oxygen atom layer or impinges upon the surface after the oxygen layer has been substantially removed by the process described and may penetrate into the oxide surface. The depth of penetration may be enhanced by the fact that the oxide surface is made thick and porous by the action of the acid etch.

If the radiation contains the proper amount of energy, it may excite one of the electrons in the F' center upon which it impinges. The F' center ionizes to emit an electron which may then travel freely throughout the oxide layer ultimately to be captured by another F center. After a time, the number of F' centers which are ionized to form F centers reaches an equilibrium with the number of F centers which recapture electrons wandering through the oxide and reform an F' center. When this equilibrium condition is reached, the number of F centers in the oxide layer is at a maximum. This process has been found to take place in less than one microsecond.

Referring now to FIG. 3 which indicates the phenomenon taking place as a shock wave 29 moves through the oxide sweeping before it a sheet of electrons 31. This sheet of electrons is generated in the metal plate or sheet 12, FIG. 2, as the shock wave sweeps through the metal driving the metal's conduction electrons before it. A few electrons may be stripped from the oxide layer but the metal serves as the main supply of electrons for this electron sheet 31. As the electron sheet passes through the oxide 11, the newly formed F' centers are quickly reconverted into F' centers with the attendant emission of a quantum of light [in the 4700 Å. range for the case of aluminum oxide centers.] When the shock wave reaches a free surface of the oxide 11 as shown in FIG. 4, a brilliant burst of light energy is given off as the reformation of F' centers from F centers takes place rapidly near the surface. This burst of light may be employed to illuminate a specimen which is to be photographed by ultra-high speed techniques, for example, a shock wave.

All the electrons in the sheet are not utilized in the reformation of F' centers. Many are available at the surface for emission into the surrounding medium as shown in FIG. 5. The Auger effect may account for this electron burst.

It should therefore be apparent that by this invention is provided a compact source of electrons or light which may be constructed of readily available materials and used for a multitude of purposes.

5
10

Having thus described this invention with reference to but one preferred embodiment, it is to be understood that it is by no means limited but is susceptible to many alterations and modifications without departing from the spirit or scope thereof. Accordingly, the foregoing illustrative example should not be construed as limiting this invention in any manner, rather the scope of the appended claims only define the invention.

What is claimed is:

1. A device for the production of short intense pulses of energy which comprises

- (1) an oxide layer having a free surface
- (2) a metal sheet bonded to a surface of said oxide layer opposite the free surface of said oxide layer, said metal being selected from the group consisting of aluminum, zinc, magnesium, cadmium, indium and gallium
- (3) explosive means contiguous with said metal sheet
- (4) radiation means directing energy upon said oxide layer and thereby activating said oxide layer
- (5) means for generating a planar shock wave by initiation of said explosive means whereby said planar shock wave impinges said metal sheet and said oxide layer and a brief pulse of energy is emitted from the free surface of said oxide layer.

2. A device for the production of short intense pulses of energy which comprises

- (1) a metal body having an oxidized surface, said metal being selected from the group consisting of aluminum, zinc, magnesium, cadmium, indium and gallium
- (2) explosive means contiguous with said metal body
- (3) radiation means directing energy upon said oxidized surface and thereby activating said oxidized surface
- (4) means for generating a planar shock wave by initiation of said explosive means whereby said planar shock wave impinges said metal body and said oxidized surface and a brief pulse of energy is emitted from the oxidized surface.

3. A method of generating an intense pulse of energy which comprises

- (1) exposing a metallic body having an oxidized surface to actinic radiation in order to activate said oxidized surface, the metal in said body being selected from the group consisting of aluminum, zinc, magnesium, cadmium, indium, and gallium
- (2) shocking said body on a surface thereof opposite said oxidized surface by means of an explosively initiated planar shock wave.
